UNITED STATES PATENT OFFICE.

WILLIAM E. LEIBING, OF OAKLAND, CALIFORNIA, ASSIGNOR TO MAGNUS FRUIT PRODUCTS CO., OF SAN FRANCISCO, CALIFORNIA, A CORPORATION OF CALIFORNIA.

DESIGN FOR A BEVERAGE-DISPENSING CONTAINER.

Application filed April 28, 1926. Serial No. 17,491. Term of patent 3½ years.

To all whom it may concern:

Be it known that I, WILLIAM E. LEIBING, a citizen of the United States, residing in the city of Oakland, county of Alameda, State of California, have invented a new, original, and ornamental Design for Beverage-Dispensing Containers, of which the following is a specification, reference being had to the accompanying drawings, forming part thereof, wherein—

I claim:—

The ornamental design for a beverage dispensing container, as shown.

In witness whereof I have hereunto signed my name to this specification.

WILLIAM E. LEIBING.
